ATTORNEY

UNITED STATES PATENT OFFICE.

JAMES H. COLLINS, OF HARRISBURG, PENNSYLVANIA.

CROSS-TIE.

1,032,045.

Specification of Letters Patent.

Patented July 9, 1912.

Original application filed September 21, 1911, Serial No. 650,493. Divided and this application filed November 15, 1911. Serial No. 660,349.

To all whom it may concern:

Be it known that I, JAMES H. COLLINS, a citizen of the United States, and a resident of Harrisburg, county of Dauphin, and 5 State of Pennsylvania, have invented certain new and useful Improvements in Cross-Ties, of which the following is a full, clear, and exact description, the same being a division of application Serial No. 650,493, 10 filed September 21, 1911.

The object of this invention is to provide an improved cross tie, or rail support, having a base provided with means for deadening the horizontal vibrations thereof 15 of, and of such shape that any vibrations in a horizontal plane will operate to solidify the ballast thereunder.

With this and other objects in view such as are brought out in the following specification and appended claims, the invention presents a construction illustrated in the accompanying drawing, in which—

Figure 1 is a side elevation of a cross tie embodying the improvements, Fig. 2 is a 25 bottom plan view thereof, and Fig. 3 is a section on the line 3—3 of Fig. 1.

Referring to the drawing, the tie consists in a hollow casing 5, slightly oblong in cross section, with a bottom wall 6 considerably thicker than the others and oppositely extending in the regions of its ends to form a reinforced supporting surface 7. The bottom wall is furthermore provided with a recess 8 increasing in depth toward 35 the transverse center, and this recess is in turn provided with a series of converging grooves 9, for a purpose hereinafter described, while extending from the recess 8 into the casing 5 are a plurality of holes 10 adapted to drain the interior of the tie, while protruding outwardly and downwardly therefrom are abrupt projections 11, best shown in their preferred form in Fig. 2. The top wall 15 of the casing is substantially flat, with its side edges 16 rounded 45 throughout a part of their length, to offer less obstruction to anything depending from vehicles passing thereover. The wall 15 is moreover provided with apertures 17, disposed centrally above the reinforced surfaces 7 of the bottom wall, and as wide as the internal width of the casing.

Arranged within the casing and protruding through the apertures 17 therefrom, 50 are blocks 18 to which the rails 19 are se-

cured, and which are constructed and designed to operate as fully described in the above mentioned co-pending application, of which this is a division.

On the outside of the casing and extending upwardly from the lateral projections of the reinforced portions 7, are webs 20, tying the projections to the side walls of the cross tie and adapted to make the latter aid in the support of the upward pressure of 65 the latter upon the former.

When placed on the road bed, the tie rests upon any well known form of ballast (not shown), which extends upwardly into the recess 8, and encircles the projections 11. 70 As is customary, the ballast is tamped beneath the tie and engaging the projections 11, and the abrupt end walls of the recess 8, prevents the tie from any material longitudinal movement. There is then left practically unrestrained the horizontal vibrations of the tie, principally those in a longitudinal direction, and these vibrations, by the construction of the recessed and grooved base, are utilized to solidify or settle the 80 ballast when once tamped thereunder, the inverted V-shaped recess tending to force the particles of ballast toward the transverse center, while the converging grooves 85 also assist to the same end in the same direction, as well as increasing the compression toward the longitudinal center.

It is not intended in the foregoing description to limit this device to the exact details of construction described, but any alterations may be made therein which do not depart from the spirit of the invention or the scope of the appended claims.

Having thus described my invention, what I desire to protect by Letters Patent of the 95 United States is:

1. A tie provided with a plurality of converging irregularities in a recess in the base thereof, said recess increasing in depth toward the transverse center. 100
2. A tie comprising the combination of a plurality of converging grooves in the base thereof, with a plurality of projections extending therefrom, each of said projections having oppositely converging walls.

3. A tie comprising the combination of a plurality of series of oppositely converging rectilinear irregularities in the base thereof, with a plurality of projections extending therefrom, each of said projections being 110

provided with oppositely disposed concave walls.

4. A tie provided with a recess in the base thereof, increasing in depth toward the transverse center, and converging means within said recess to cause the solidification of the ballast thereunder by the horizontal vibration of said tie.

5. A tie provided with a recess in the base thereof, increasing in depth toward the transverse center, and means converging alternately in opposite directions within said recess to cause the solidification of the ballast thereunder by the horizontal vibrations of said tie.

6. A tie provided with a recess in and extending throughout the greater portion of the base of said tie, said recess increasing in depth toward the transverse center thereof, and means converging alternately in opposite directions within said recess, to cause

the contraction of the ballast thereunder by the longitudinal vibrations of said tie.

7. A tie provided with a recess in and extending throughout the greater portion of the base of said tie and recess, increasing in depth toward the transverse center thereof, means converging alternately in opposite directions within said recess to cause contraction of the ballast thereunder by the longitudinal vibrations of said tie, and means integral with and projecting from base of said tie to prevent longitudinal movement thereof.

In witness whereof, I have hereunto set my hand this 10th day of November, A. D., 1911.

JAMES H. COLLINS.
